(57) **CLAIM**

The ornamental design for a motor housing, as shown and described.

DESCRIPTION

FIG. 1 a perspective view of a motor housing according to our new design, with environmental exploded components shown in broken lines;

FIG. 2 is a perspective view of a cap of the motor housing thereof;

FIG. 3 is a top perspective view of the motor housing;

FIG. 4 is a bottom perspective view thereof;

FIG. 5 is a front perspective view thereof;

FIG. 6 is a rear perspective view thereof; and,

FIG. 7 is a left side perspective view thereof.

The broken line showing portions of a motor housing is included for the purpose of illustrating environmental structure and forms no part of the claimed design.
